(57) **CLAIM**

The ornamental design for a stopper for a top or bottom latch, as shown and described.

DESCRIPTION

FIG. 1 is a top, perspective view of a stopper for a top or bottom latch showing my design;

FIG. 2 is a bottom, perspective view thereof;

FIG. 3 is a front elevational view thereof;

FIG. 4 is a rear elevational view thereof;

FIG. 5 is a left elevational view thereof;

FIG. 6 is a right elevational view thereof, the phantom lines being for illustrative purposes only and forming no part of the claimed design;

FIG. 7 is a top plan view thereof; and,

FIG. 8 is a bottom plan view thereof.

The broken lines depict portions of the article that form no part of the claimed design.

1 Claim, 8 Drawing Sheets(56)
